UNITED STATES PATENT OFFICE.

EGERTON A. BLISS, OF NEW YORK, N. Y., ASSIGNOR TO THE E. A. BLISS COMPANY, OF SAME PLACE.

DESIGN FOR A MATCH-SAFE.

SPECIFICATION forming part of Design No. 20,586, dated March 17, 1891.

Application filed January 28, 1891. Serial No. 379,453. Term of patent 7 years.

To all whom it may concern:

Be it known that I, EGERTON A. BLISS, a citizen of the United States, residing at New York, in the county of New York and State of New York, have invented a certain new and original Design for Match-Safes, of which the following is a full, clear, and exact description.

In the accompanying drawings, Figure 1 is a perspective view of one face of a match-safe, showing my design; and Fig. 2 is a perspective view of the other face of the match-safe having my design thereon.

The leading feature of my design is a match-safe which has a close resemblance to a mail-pouch; and with this end in view I produce the match-safe with a body having an imitation of the straps, hoops, and lock for fasten-

ing the pouch, as shown at A, and I also represent the seams S as they appear in an ordinary pouch. On one face of the match-safe I arrange a panel, upon which may be placed appropriate words, such as "U. S. Mail," and on the other face I show a number of envelopes promiscuously scattered over the surface, as shown at C.

What I claim is—

The design for a match-safe, herein shown and described.

In testimony whereof I affix my signature in presence of two witnesses.

EGERTON A. BLISS.

Witnesses:

WILBUR F. DAVIS,
H. E. SHARPS.
